UNITED STATES PATENT OFFICE

HARRY T. RANDLE, OF LAWRENCE, KANSAS

GARAGE CONSTRUCTION

Application filed September 7, 1926. Serial No. 133,871.

My invention relates to a building construction and more particularly to a garage construction.

It is a purpose of my invention to provide a new and improved garage construction into which the automobiles are brought to a parking space under their own power and are removed from the garage under their own power or by a separate power operated device to thus facilitate the delivery of the automobiles from the garage.

More particularly, my invention comprises a garage construction that is provided with a continuous spiral parking and driving surface extending from the bottom to the top of the building in proper spaced relation to the roof which is inclined in such a manner as to provide the proper drainage therefor. Furthermore, the garage construction preferably includes a spiral runway or track adjacent the center thereof which is provided with means for moving vehicles therewith, said means preferably comprising a flexible member, and means for attaching the vehicles thereto.

It is a further purpose of the invention to provide means for moving said flexible member comprising a rotatable member, preferably in the form of a drum, with which the flexible member is engaged, said drum being rotated by means of a motor and being provided with brake mechanism similar to that used in connection with elevators, that is applied when the speed of the flexible member reaches a predetermined limit. Means is also preferably provided for controlling the operation of said motor at a plurality of points along the flexible member so that the means for moving the vehicles can be halted at a plurality of points along the flexible member to permit the attachment of a vehicle thereto in such a manner that the same will be propelled to the exit of the building.

It is still a further purpose of my invention to provide means for automatically breaking the circuit to the motor when the vehicle reaches the point adjacent the exit of the building so that the vehicle may be detached from the flexible member.

The inclined spiral parking and driving

surface is preferably provided with a plurality of drain grooves running toward the center and preferably substantially radially thereof that connect with an intersecting preferably arcuate groove from which a drain pipe leads out of the building, thus preventing the accidental accumulation of inflammable liquids on the parking and driving surface. The building is also preferably provided with an elevator shaft at the center thereof, substantially in the center of the spiral track so that attendants may enter and leave the various levels that will exist, due to the spiral construction of the floor or driving surface. In order to prevent undue wear on the tires and to provide suitable means for engaging the vehicle with the track a wheeled member is preferably provided that may be attached to one of the axles of the vehicle and which engages with grooves in the floor that serve as the spiral track at the center of the building surrounding the elevator shaft.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a vertical sectional view of my improved garage.

Fig. 2 is a transverse sectional view taken substantially on the line 2—2 of Fig. 1.

Fig. 3 is a fragmentary perspective view of a portion of the track and of a vehicle associated therewith showing my improved wheeled track engaging means.

Fig. 4 is a fragmentary view, partly in perspective and partly in section, of a portion of a vehicle and the means for moving the same along the track showing the vehicle attached to such means.

Fig. 5 is a fragmentary sectional view of the automatic circuit breaking means.

Fig. 6 is a diagrammatic view of the circuit employed in connection with the operating means, and,

Fig. 7 is a fragmentary perspective view 5 of the flexible vehicle propelling member showing the gripping clamp attached thereto.

Referring in detail to the drawings:

My improved garage construction comprises side walls 10, a rear wall 11, a front wall 12 and a roof 13. Extending from the entrance openings 14 in the front wall portion 12 to the roof 13, is a continuous floor which serves as a driving and parking surface indicated by the numeral 15, said floor 15 being a spiral, extending with continuous uniform inclination from the entrance openings 14 to the upper end portion 16 thereof adjacent the roof 13. Obviously any portion of the floor 15 may be used for driving or 20 parking purposes but preferably in order to define into parking and driving spaces, the floor is provided with suitable markings which may be arranged in any desired manner and are accordingly not indicated on the 25 drawings, so as to divide the floor into driving lanes and parking spaces in the manner that is found to be the most desirable and most convenient.

Preferably at substantially the central 30 point in the building, a circular wall portion 17 is provided, said wall portion being provided preferably with openings 18 and defining an elevator shaft 19 within which the elevator 20 may be placed, the same being 35 operated in the usual well known manner, operating means 21 therefor being preferably mounted in a pent-house 22. While it is not absolutely necessary that the space 19 be utilized as an elevator shaft, this has been found 40 highly desirable for the sake of compactness as otherwise the space at the center of the building would not be capable of utilization.

A pair of spiral grooves 23 is preferably 45 provided in the floor 15 at the inner edge thereof, that is, at the edge adjacent the wall 17. The grooves 23 extend in a continuous spiral from the upper end 16 of the floor to the lower end thereof, terminating at the 50 point 24 adjacent the wall 17 as will be clearly seen from Fig. 2. A groove 25 is also preferably provided in the floor between grooves 23 and a pair of plates 26 preferably overhang the upper open end of the groove 25 55 so as to provide a slot 27 through which the cable gripping member 29 extends. The flexible member 30 operates in the groove 25 and extends over the drum 31 and from said drum substantially vertically upward to the pulley 32 and then back to the groove 25. The drum 31 is rotated by means of an electric motor 33 and a brake mechanism 34 is preferably 60 provided between the motor and the drum that is governor controlled in the usual manner of elevator brake mechanisms, to prevent

the movement of the flexible member 30 from exceeding a predetermined speed limit. Referring now to Fig. 6, which diagrammatically shows the controlling means for the motor 33, it will be seen that the current for the motor 33 is obtained from the line wires 35 in which the main switch 36 is mounted, connecting the same with the conductors 37 leading to a control switch 38 from which the wires 39 extend to the motor 33 and ordinarily also to the braking means 34. The controller 38 is actuated by means of the controller circuit comprising the conductors 40 and 41 which lead into the switch 38, the controller operating current being obtained from any suitable source of power 42 such as a battery, and a plurality of switches 43 being interposed in the conductor 41. It will be seen that when all the switches 43 are closed, current will flow through the controller circuit comprising the conductors 40 and 41 and will actuate the controllers so as to close the circuit 43 and release the brake 34. The conductors 40 and 41 preferably extend upwardly along the inner edge portion 70 of the floor 16 conveniently close to the track, formed by the grooves 23 so that the operation of the flexible member 30 can be halted 75 by opening of one of the switches 43 at a point in close proximity where it is desired 80 to remove an automobile from the parking surface. One of the switches indicated in the diagram by the numeral 43 may be an automatic switch that will break the circuit when 85 the vehicle reaches the discharge end 24 of the track which will be described below.

In placing the vehicle in engagement with the track, a wheeled member or truck is first connected with the front axle 44 of said vehicle. Said wheeled member comprises an axle 45 upon which the wheels 46 are mounted that engage with the grooves 23. Mounted on the axle 45 is an upstanding bracket member 47 which may be provided with a fifth wheel member 48 co-operating with a fifth wheel member 49 having a clamping bracket 50 thereon. The clamping bracket 50 preferably comprises a forward extension 51 from which the bolt 52 extends upwardly. The bracket member 50 is further provided with upward extensions 53 to which is pivoted the forked member 54 providing a slot 55 in which the bolt 52 engages, said bolt being provided with a winged nut 56 for clamping the member 54 in engagement with the axle 44. When the wheeled member connected with the front axle is to be put in place, one of the switches 43 is opened to stop the member 30, thus preventing the movement of any other vehicle that may be 100 attached to the member 30 and avoiding collision with a vehicle that is to be attached to said member. After the wheels 46 have 105 been engaged with the grooves 23, the rear end of the vehicle is attached to the flexible 110 member 30, the member 30 being rotated by the motor 33, the vehicle being moved along the track 115 and the flexible member 30 being wound around the drum 31. The vehicle is then stopped by the action of the motor 33 and the flexible member 30 is wound around the drum 31, the vehicle being 120 then moved in the reverse direction. The vehicle is stopped by the action of the motor 33 and the flexible member 30 is wound around the drum 31, the vehicle being 125 moved in the reverse direction. The vehicle is stopped by the action of the motor 33 and the flexible member 30 is wound around the drum 31, the vehicle being 130 moved in the reverse direction.

member 30 by attaching the grip clamp 29 thereto as shown in Fig. 7 to which one end of the flexible member 58 is attached, the other end of the flexible member being first looped around the rear axle 59 of the vehicle, by first passing around the axle 59 and then through the eye member 60 to form the loop around said axle. The vehicle will thus be moved with the rear end foremost in a downward direction around the spiral track to the lower end 24 thereof.

Mounted in a recess 61 in the floor 15 connecting with one of the grooves 23 is a switch mechanism for automatically breaking the circuit to the motor when the vehicle reaches the lower end 24 of the runway or track. Said switch mechanism comprises a fixed contact 62, and a movable contact 63, said fixed contact 62 being mounted on the bracket 64 to which one portion of the conductor 41 leads and a movable contact 63 is mounted upon an arm 65 of a pivoted member having the pivot 66, the other portion of the conductor 41 being connected with said contact 63. Extending from the pivot 66 in an opposite direction from the arm 65 is an arm 67 of said pivoted member which is made in the form of a plate-like member lying in the groove 23. A compression spring 68 is preferably mounted between the plate 67 and the bottom of the groove 61 and a spring catch member 69 having an offset portion 70 adapted to engage with the end of the plate 67 is provided in the groove to hold the plate in a downward position in the groove against the tension of the spring 68 when the same has been depressed by a wheel 46 engaging with the same. It will thus be seen that when one of the wheels 46, associated with a vehicle that is coming down the runway or track, engages with the plate 67, the control circuit will be broken, thus actuating the control switch 38 to stop the motor 33 and said switch will be locked in open circuit position.

The same can of course be manually closed by releasing the plate 67 when the vehicle has been removed from the lower end 24 of the track, thus restoring the operating means to operative condition.

Preferably, the floor 15 is provided with a plurality of transverse drain grooves 71 which preferably extend in a radial direction and which connect with an intersecting curved groove 72 that leads to a drain pipe 73, thus providing for the drainage of any liquid, that may accumulate on the floor and which may be inflammable, out of the building. The floor 15 is, of course, supported at suitable intervals by means of columns 74 which may be spaced at desired points about the building so as to properly support the weight of the vehicles and the floor.

What I claim and desire to secure by Letters-Patent is:—

1. In a garage construction including a central circular wall, a continuous spiral floor having its inner edge at the circular wall, said floor being provided with a track on its surface at its inner edge forming a continuous spiral runway adjacent the circular wall.

2. In a garage construction, a building including a central circular wall, a continuous spiral floor having uniform inclination from the bottom to the top of the building and having an inner edge at said wall, a track comprising spaced grooved floor portions at the inner edge of the floor forming a continuous spiral runway having uniform inclination from the bottom to the top of the building, and means including a cable operating between said grooved floor portions for controlling movements of vehicles on said track.

In testimony whereof I affix my signature.

HARRY T. RANDLE.
